UNITED STATES PATENT OFFICE.

LOUIS P. DISS, OF ILION, NEW YORK.

TYPE-WRITING MACHINE.

1,322,676.

Specification of Letters Patent. Patented Nov. 25, 1919.

Application filed March 1, 1917. Serial No. 151,836.

To all whom it may concern:

Be it known that I, LOUIS P. DISS, of Ilion, in the county of Herkimer and State of New York, have invented certain new and useful Improvements in Type-Writing Machines; and I do hereby declare that the following is a full, clear, and exact description thereof, which will enable others skilled in the art to which it appertains to make and use the same, reference being had to the accompanying drawings, and to the reference-numerals marked thereon, which form part of this specification.

My present invention relates to typewriting machines.

The object of my invention is to provide means whereby better alinement, better spacing and better type impressions will be effected and greater speed attainable.

A further purpose of my invention is to provide an improved form of type bar and type bar mounting and connections and furthermore to provide a novel and improved combination thereof with the escapement mechanism.

Another purpose of this invention is to provide improvements in the escapement mechanism and the connection thereof with the rest of the typewriting machine.

It is well known that the large number of type bars contained in the segment of a front-strike typewriting machine necessitates the pivots of the type bars being short as compared with the length of the type bars themselves so that the slightest looseness of the type bar pivots in their bearings will effect a magnified deviation from alinement and cause irregularity in spacing. One purpose of my invention is to eliminate this deviation and irregularity by providing spring pressure against the type bars whereby the pivots will be forced against one side of their bearings instead of being free to take various bearings which the looseness would otherwise permit. Furthermore I provide novel and improved means for effecting this purpose.

Further purposes and advantages of my invention will appear from the specification and claims herein.

I have shown my improvements applied to what is known as a No. 10 Remington typewriting machine, but it will be obvious that my invention is not limited in its appli-

cation to that machine, but may obviously be applied to many other machines.

Figure 1 is a vertical sectional view through the material parts of a typewriting machine embodying one form of my invention.

Fig. 2 is a rear elevation of the segment and the auxiliary universal bar.

Fig. 3 is a vertical sectional view of the segment and adjacent parts of a typewriter embodying another form of my invention.

Fig. 4 is a side view of an escapement device embodying one feature of my invention.

Fig. 5 is a rear elevation of a part of a segment as shown in Fig. 3 and of an escapement device as shown in Fig. 4.

Fig. 6 is an edge view on an enlarged scale of the pivoting end of a type bar.

Figs. 7 and 8 are edge and side views respectively on a similarly enlarged scale of a type bar hanger embodying one feature of my invention.

Fig. 9 is a perspective view of the holding dog of the escapement device and Fig. 10 is a perspective view of the spacing dog of the escapement device, both upon an enlarged scale.

Referring to the drawings in a more particular description, it will be seen that for the sake of clearness I have shown only two type bars 15 and 16 and two type bar hangers 17 and 18, but these are illustrative of the usual two series of type bars and type bar hangers arranged in the usual radial fashion upon the front face of a segment 19 of form usual to front-strike typewriting machines. The type bars are pivotally mounted in their respective type bar hangers by means of oppositely disposed outwardly extending short pivots 20 near one end of each type bar being mounted in bearings 21 upon the forwardly extending wings of the type bar hanger in the way well known in the art so that a forward pull upon the connecting rods 22 operatively connecting the heel of the type bars to the key levers 22^a operates to raise the type bars from substantially horizontal position to upright or printing position against the platen 63.

On account of the number of type bars which must be mounted upon the limited surface of the segment of the usual front-strike typewriter the pivots upon each type

bar must be very short relative to the length of the type bar. As the type bar must move very freely in its bearings it is obvious that there will be some looseness of the type bar 5 pivots in the bearings and that this looseness will be as it were multiplied or magnified in the length of the type bar resulting in a considerable lateral deviation of the type upon the type bar being possible according 10 to whether the type bar has swung to one side or the other in its bearings as it was making its main upward movement to printing position. I have overcome this trouble by providing means whereby the type bar is 15 pressed to one side of its bearings particularly as it approaches printing position.

As means for exerting this pressure I provide pins 23 slidingly mounted in the segment 19 preferably as by being mounted 20 in bushings 24 which in turn are fixed in the segment, said pins being spring-tensioned to move to forward position and being so arranged that their forward ends project out from their mountings and yieldingly engage 25 shoulders 25 upon the type bars 15 and 16 as said type bars approach upright or printing position. The spring tension from said pins it will be obvious is not sufficient to prevent the type bars from coming to full printing 30 position, but is sufficient especially in view of its being exerted close to the pivots 20 to cause the pivots 20 of the said type bars to be pressed to one side of their bearings as the type bars approach printing position. It will be seen that this pressing of 35 the type bar pivots to one side of their bearings obviate the lateral deviation of the type bars by reason of the fact that the type bars as they come to printing position are 40 always in one position relative to their bearings and the type bar being properly adjusted to make its impression on the platen in a proper position, subsequent impressions will be in the same position. The pins 23 45 are provided with heads 26 to limit their forward movement in their mountings and determine the commencement of the spring pressure on the type bars relative to the position of the type and platen. As the type 50 bars 15 and 16 and type bar hangers 17 and 18 and pins 23 are arranged, it will be seen that the type bar pivots 20 are pressed to the forward side of their bearings 21 as they approach printing position. It is not essential 55 that the type bars be pressed to the front of their bearings as they may obviously be pressed in any given direction as long as the arrangement of parts is such that the several type bars are always subjected 60 to pressure in the same direction as they approach printing position. The arrangement of parts shown, however, is a preferred form upon a machine of the class illustrated as it gets the desired result with 65 a minimum of additional parts and without

changing the usual arrangement of parts upon the typewriting machine and also because the pull of the connecting rods 22 tends to pull the pivots forward in their bearings. 70

In order to have the pressing of the type bar pivots to one side of their bearings be most effective and most uniform, I prefer to have the side of the bearings to which the type bar pivots are pressed V-shaped or 75 crotch-shaped as they will assist the spring pressure to most readily and most uniformly bring the type bar to uniform position as it approaches printing position.

It is obvious that various means may be 80 used to exert the necessary spring pressure upon the heads of the pins 23. One simple method of accomplishing this is shown in Figs. 3 and 5 of the drawings wherein resilient tongues 27 extend inward close to 85 the back surface of the segment 19, said tongues being held in place relative to the segment at their outer end by convenient means as by being formed as part of a single band 28 curved to fit and securely affixed to 90 the outer periphery of the segment 19 as by screws 29.

Another form of providing the necessary forward spring tension for the pins 23 is shown in Figs. 1 and 2 particularly and consists in having an auxiliary universal bar 30 segment-shaped in outline as clearly indicated in Fig. 2 and of such size and so placed at the back of the segment 19 as to cover the heads 26 of all of the pins 23. 95 This auxiliary universal bar 30 is held by spring tension against the heads of the said pins, but is adapted to yield and move rearwardly in a parallel direction as any of the type bars are moved to printing position 100 and the rearward movement imparted to it by a pin 23 against the spring tension of the auxiliary universal bar 30 performs the function already described in detail of pressing the pivots of the type bar to one side 105 in their bearings. 110

The auxiliary universal bar 30 is operatively connected to the escapement mechanism so that rearward movement of said bar 30 to the proper extent operates or may 115 operate the escapement mechanism and meanwhile the said bar 30 is at all times held under spring tension to move in forward direction under the impulse of the spring forming a part of the escapement device. The means provided for holding the segment-shaped auxiliary universal bar 30 in position so that it may move slightly from the segment 19, but be at all times parallel thereto, consists of two L-shaped 120 brackets 31 having their upper ends rigidly fastened as at 32 to opposite points upon the back of the auxiliary universal bar while the main part or leg of the bracket extends 125 downward toward the back of the machine 130

and the foot 33 of the L-shaped bracket extends forwardly over rocker shaft 34. The brackets 31 at their angle points 35 are pivotally supported in arms 36 upstanding from a shaft 37 extending transversely of the machine and supported in any suitable way upon the frame work of the machine. The forward ends of the foot pieces 33 are at 38 pivotally supported in the upper ends 10 of arms 39 extending upward from the transversely extending shaft 34. It will now be obvious that the two brackets 31 with their pivotal support upon four links provide the proper parallel movement for 15 the auxiliary universal bar 30.

In the full embodiment of my invention, as shown in Figs. 1 and 2 particularly, one of the transverse shafts preferably the forward one 34, is the rock shaft through the 20 crank arms 40 of which by means of connecting rod 41 going down to the main universal rod 41^a there is received the movement to operate the escapement device. This movement through crank arm 42 and connecting 25 rod 43, is transmitted up to the escapement device whereby each depression of any key lever to the proper extent operates the escapement device.

The escapement device employed and 30 shown in the drawings is in its construction and operation substantially like the escapement shown in Patent No. 1,021,182 granted to me March 26, 1912 so that only a brief description of said mechanism is necessary 35 here except as to the improvements thereon shown in this present application. The escapement wheel 44 having the usual teeth 45^a is mounted to revolve in a vertical plane parallel to the line of the movement of the carriage and operatively connected therewith and with the main spring in the usual well-known manner, not shown in the drawings. The tension of the main spring is to revolve 40 the escapement wheel in the direction indicated thereon in the drawings by an arrow. The dog rocker 45 is provided with pivots 46 and 47 suitably supported in parts provided upon the frame of the machine but for the sake of clearness not shown. The axis 45 of the dog rocker is at right angles to the axis of the escapement wheel. Pivotally mounted at 48 upon the dog rocker 45 and having its pivotal axis at right angles with the axis of the dog rocker is the stepping or 50 spacing dog 49 which extends upward and engages a tooth 45^a of the escapement wheel 44 when the machine is not being operated which is the position of the parts in Figs. 3 and 5 and which for convenience I will call 55 the normal position. A shoulder upon the dog rocker limits the movement of the spacing dog 49 to the left as shown in Fig. 5 where the spacing dog will hold one of the escapement teeth in desired position. A 60 spring 50 upon the dog rocker 45 bears upon

the spacing dog 49 so as to throw it toward the right as viewed in Fig. 5 when the rocking movement of the rocker 45 carries the spacing dog out of engagement with the escapement wheel. A spring 51 connected at 70 one end to a suitable projection upon the rocker 45 and at the other to a convenient fixed part of the machine frame yieldingly holds the rocker in such position that the spacing dog 49 is in engagement with the 75 escapement wheel 44 but allows the rocker to be moved so that its upper part swings to the left as the parts are seen in Figs. 1 and 4 whereby the holding dog 52 is brought into line with the teeth of the escapement wheel. 80 The holding dog 52 is rigidly connected to its shaft 53 from which extends a crank arm 54 as most plainly seen in a perspective view thereof, Fig. 9. The shaft 53 of said holding dog is pivoted upon arms 55 and 56 upon 85 opposite sides of the dog rocker so that the axis of said shaft is at right angles to the axis of the dog rocker. The crank arm 54 extends to the right as the parts are seen in Fig. 5 and is upon the opposite side of the 90 axis of the dog rocker relative to the holding dog 52 so that downward movement imparted to connecting rod 43 from either universal bar swings the holding dog to the right upon the holding dog axis as the parts 95 are seen in Fig. 5, and also swings the dog rocker upon its axis so that the spacing dog 49 is disengaged from the tooth of the escapement wheel and the holding dog 52 is brought laterally into engagement therewith. As the holding dog is positively and directly connected back to the key levers it will be seen that the escapement wheel is held against its tendency to move as long as the key levers are held depressed. As soon 100 as the pressure upon the key levers is released the movement of the escapement wheel begins at once since the holding dog is forced directly back by the escapement wheel while the holding dog is meanwhile 105 being moved laterally by the return of the dog rocker to normal position so that the spacing dog is brought into position to engage the next tooth of the escapement wheel. 110

It will be seen, however, that for the purpose of using the features of my invention involving the spring pressure upon the type levers near their pivots and a spring-tensioned auxiliary universal bar, the escapement mechanism here shown and described 115 is not essential since a great many of the escapement devices in use are of such construction that there is a spring-tensioned connecting rod moved at each operation of the escapement device in a manner similar to the 120 connecting rod 43 here shown.

The escapement device here shown, however, has the further advantage that the escapement wheel is held positively in printing position by reason of the direct connec- 130

tion of the holding dog back to the key levers resulting in a combination between the escapement device here shown and the features of spring pressure and auxiliary universal bar which is very advantageous and efficient.

The escapement device shown in the present application is a modification of and an improvement upon that shown in my previous Patent No. 1,021,182 in that in the present device the holding dog when brought toward the normal position of the spacing dog is not brought into line therewith, but is a step back from the engaging face of the spacing dog as plainly indicated in dotted outline at 52^a in Fig. 5. This construction results in greater speed and efficiency in the machine in that a portion of the letter space movement of the carriage and platen is made before the type reaches the platen and whereby less movement of the carriage and platen is needed to complete the escapement movement after the type has made its impression upon the platen. It will be seen that the first part of the movement transmitted from the key levers will bring the holding dog forward to holding position and move the dog rocker and said spacing and holding dogs laterally whereby the holding dog is brought into engagement with the escapement wheel. By reason of the step between the normal position of the spacing dog and the holding position of the holding dog the escapement wheel is allowed to make a part of its movement, but is then held temporarily from further movement while the type impression is made through the engagement of the holding dog with the escapement wheel, bearing in mind that the holding dog is directly operatively connected to the key levers so that as long as the key levers are being depressed or held down the escapement wheel cannot move. While the escapement wheel is thus held in this intermediate position the type bar completes its movement toward the platen and the impression is made. Instantaneously with the removal of pressure upon the key levers the escapement wheel is free to move and does move pushing the holding dog back as the holding dog is at the same time allowed to move back and is swung laterally out of engagement with the escapement wheel. It will be seen that this construction results in great speed of the machine in that a portion of the letter space movement of the carriage is made before the type reaches the platen which would otherwise be waste time and thus shortens up the time necessary after a type impression has been made for the completion of the escapement movement because only a part of the complete movement remains still to be made. The arrangement and adjustment of parts is such that the type under its highest velocity will

reach the platen at the same time that the tooth of the escapement wheel reaches the holding dog. It will be seen, therefore, that when the machine is being manipulated by an expert high speed operator a great speed is attainable in that the carriage will not be stopped by the holding dog and at the same time such construction of the machine will not impair its efficiency for use by moderately skilled operators. In fact the said construction will result in greater speed of the machine even when used by unskilled operators.

It will be seen also that the escapement device here shown combining as it does the step between the spacing and the holding dog and the holding dog positively held by the key lever combines very efficiently the feature of desirable high speed and also the equally important factor of a definite type impression in that the platen is positively held as long as pressure on the key lever continues so that no movement of the platen is allowed during the time when the type is in contact with the platen thus avoiding blurred or double impressions.

With these features my machine also combines the auxiliary universal bar operated directly by the type bars whereby the escapement device and type impression may be much more efficiently and positively connected. In practice preferably the parts as shown in the drawing will be so arranged that while the main movement of the escapement device is started and carried on through the main universal bar the last part of the escapement movement will be brought about by the auxiliary universal bar being actuated by the type bars so as to overtake the other movement and so complete the escapement movement at the instant the type impression has been made. But it will be obvious from the construction already described and shown in the drawings that the so-called main universal bar may be entirely eliminated as far as spacing when type impressions are made and that the necessary operation of the escapement device at such times may be performed through the so-called auxiliary universal bar being operated by the type bars moving the pins 23.

It will be seen also that the provision I make for the type bars being held to one side of their bearings by spring pressure upon the type bars as they approach printing position allows me to make a looser-jointed machine than would otherwise be practical and so a machine more easily operated and consequently capable of greater speed. Furthermore the provision for the slight spring tension against the type bars will also operate to hasten their movement away from the platen after the type has made its impression thus assisting in greater speed of

the machine and will also prevent any rebounding of the type bars thus effecting better and clearer type impressions.

What I claim as new and desire to secure 5 by Letters Patent is:

1. In a typewriting machine the combination of a type bar hanger having oppositely disposed bearings, a type bar having two oppositely disposed laterally extending 10 pivots supported in the hanger bearings, the side of the bearings toward which the type bar pivots are pressed being crotch-shaped, and a spring-tensioned member adapted to come into engagement with said type bar 15 near its pivotal support as the type bar approaches printing position whereby the type bar pivots are pressed against said crotch-shaped side of their bearings insuring uniformity of position of the type bar 20 at printing.
2. A typewriting machine having a spring tensioned universal bar, an escapement device operated therefrom, a type bar hanger support, two spaced series of type bar hangers on said support, type bars pivotally mounted in said supports and guided solely 25 on said support, type bars pivotally mounted in said supports and guided solely

thereby and means for operatively connecting the type bars to the universal bar whereby the type bars operate the universal bar and the type bars are pressed to one side of 30 their pivoted bearings by the tension from the universal bar, one series of said connecting means being arranged between the two series of hangers.

3. A typewriting machine having a spring 35 tensioned universal bar, an escapement device operated therefrom, a type bar hanger support, two spaced series of type bar hangers on said support, type bars pivotally mounted in said supports and guided solely 40 thereby and pins slidably mounted in the hanger support and adapted to operatively connect the type bars and the universal bar whereby the type bars are pressed to one side of their pivotal bearings by the tension 45 from the universal bar, one series of said pins being arranged between the two series of hangers.

In witness whereof I have affixed my signature, this 8th day of February, 1917.

LOUIS P. DISS.
